UNITED STATES PATENT OFFICE.

JOSEPH J. WALSER AND HUBERT LANG, OF CHICAGO, ILLINOIS, ASSIGNORS TO THE GOSS PRINTING PRESS COMPANY, OF CHICAGO, ILLINOIS, A CORPORATION OF ILLINOIS.

PRINTING-PRESS.

1,197,876.

Specification of Letters Patent. Patented Sept. 12, 1916.

Application filed September 27, 1915. Serial No. 52,872.

To all whom it may concern:

Be it known that we, JOSEPH J. WALSER and HUBERT LANG, citizens of the United States, residing at Chicago, in the county of Cook, State of Illinois, have invented certain new and useful Improvements in Printing-Presses, of which the following is a specification, reference being had to the accompanying drawings.

10 This invention relates to printing presses and it has for one of its objects the provision of a new and improved arrangement of press parts and driving means, by which a very great flexibility is attained in the matter of the products capable of being produced.

15 It is another object of our invention to provide new and improved driving means by the use of which power can be applied from one or another source to the various press elements. By this means, there is provided a plurality of driving elements any one of which is capable of driving a given selected press section. At the same time, 20 each driving element can be operatively connected up with a plurality of different press sections for operating them in coördinate relation to each other, or a plurality of driving elements can be operatively connected up 25 with a plurality of such press sections.

30 It is one of the specific objects of our invention to provide a press made up of a plurality of sections which can be operated as three octuples, four sextuples, or six quadruples as occasion may require, either by an equipment of four motors or six motors.

35 It is another object of our invention to improve printing presses of this type in sundry details hereinafter pointed out.

40 The preferred means by which we have accomplished our several objects are illustrated in the drawings and are hereinafter specifically described.

45 That which we believe to be new and desire to cover by this application is set forth in the claims.

In the drawings.—Figure 1 is a top view of one end portion of our complete printing press, Fig. 2 being a continuation of Fig. 1 50 to the left, showing the other end portion of the press; Figs. 3 and 4 are side elevations, respectively, of the press portions shown in Figs. 1 and 2; Figs. 5 and 6 are top views of the respective end portions of the 55 press, showing the means for driving the

various press sections; Fig. 7 is an end view of the press as seen substantially on line 7—7 of Fig. 1, showing both the press elements and the driving elements located upon the press floor and in the pit underneath the press; Fig. 8 is a view taken substantially on line 8—8 of Fig. 1; Fig. 9 is an enlarged detail of one of the three sets of driving mechanism employed; and Fig. 10 is an end view of the parts shown in Fig. 9.

In the various figures of the drawings the parts are shown more or less diagrammatically, our invention being directed more to the general construction and arrangement than to the detailed construction of the separate parts.

The press as a whole comprises twelve press sections A, B, C, D; E, F, G, H, I, J, K, and L arranged in two rows parallel to each other, each press section comprising a printing couple four plates wide adapted to print sixteen pages at each complete revolution of the cylinders. Each press section is provided with four angle-bars 20 suitably supported in position for any desired association of the printed webs, as will be readily understood. Formers 21 and 22 are provided adjacent to the press sections C and D; formers 23 and 24 are provided adjacent to the sections E and F; and formers 25 and 26 are provided adjacent to the sections I and J. The printed webs after having been run over the formers 21 to 26, respectively, for receiving their longitudinal fold are directed to suitable transverse folding mechanisms 27 (see Fig. 8), one such folding mechanism being provided in suitable position beneath each of the formers. Transfer mechanisms 28 of any suitable type are provided for carrying the complete folded product from one side of the press to the other, as best shown in Fig. 8. Each press section before the commencement of a printing operation is provided with a roll of paper 29 which is threaded through the machine in the well-understood manner.

Inasmuch as the parts so far referred to are of any suitable type and form in and of themselves no part of our present invention is believed to be unnecessary to further describe them herein.

The driving elements of the press comprise motors M, N, O, P, Q, and R located in a pit or pits below the level of the floor

upon which the press proper is located. The driving elements of the press further comprise a plurality of variable speed mechanisms S, T, U, V, W, and X which are adapted to be connected up with the several motors in various combinations, as herein-after described. In the construction shown, each of these variable speed mechanisms is substantially of the type shown in Letters Patent of the United States, to Evensen, granted April 4, 1911, No. 988,560. The driving elements of the press also comprise shafts 30, 31, 32, 33 and 34 at one side of the machine, and shafts 35, 36, 37, 38 and 39 at the other side of the machine. The several shafts are adapted to be connected together in series, as shown, by means of clutches 40, 41, 42, 43, 44, 45, 46, and 47, any one or more of which clutches can be thrown into operation as may be desired. Each of the press sections is adapted to be driven by power from one or the other of said lines of shafting by means of intermeshing bevel gears 48-49, the bevel gear 48 being connected with the press mechanism by any suitable train of driving mechanism.

The connections between the several motors and the several press driving shafts through the various variable speed mechanisms S, T, U, V, W and X comprise main driving shafts 51, 52, 53 and 54 at one side of the press and main drive shafts 57, 58, 59 and 60 at the other side of the press. The shafts 52, 53 and 54 are connected in series by clutches 63 and 64; and the shafts 57, 58 and 59 are connected in series by clutches 67 and 68,—each of these clutches being of any suitable type adapted to cause rotation in unison. The motors M, N, O, P, Q and R are connected up with the shafts 51, 57, 58, 53, 54 and 60, respectively, by means of endless chains 70 operating upon suitable driving wheels 71-72.

The connections between the line of press driving shafting at each side of the machine and the main driving shafts at that side of the machine comprise intermediate driving shafts 73, 74, 75, 76, 77 and 78 which are connected in the train of driving parts as hereinbefore described. The shafts 73 and 76 are connected so as to rotate together by means of a chain 79 operating upon driving wheels 80-81; the shafts 74 and 77 are connected by means of a chain 82 and driving wheels 83-84; and the shafts 75 and 78 are connected by means of a chain 85 operating upon driving wheels 86-87.

Each of the variable speed mechanisms S, T, U, V, W and X comprises a counter-shaft 88 provided with a gear 89 and with a clutch member 90, both mounted thereon so as to rotate therewith. A large gear 91 is revolvably mounted upon each of the counter-shafts 88 provided with a clutch mem-

ber 92 adapted to be thrown into operative engagement with the clutch member 90 for causing the gear 91 to rotate with said shaft. The gear 91 meshes with a pinion 93 fixed upon the main driving shaft. Braking devices 94 of any suitable type are mounted upon the countershafts 88. Clutch members 95 are mounted upon the main drive shafts adapted to be thrown into operative engagement with clutch members 96 which are adapted to rotate with large gears 97 which are carried by sleeves 98 mounted upon said main drive shafts, the gears 97 being in mesh with the gears 89. With the main drive shafts being driven by one or another of the motors before-mentioned, by a proper manipulation of the clutch members 90-95 by means not shown, the sleeves 98 will be driven either at the same speed as that of the main drive shafts or at a very materially slower speed by reason of transmission through the counter-shafts 88, as is fully described in the Evensen patent above referred to.

Fixed upon the sleeve 98 which is revolvably mounted upon the main driving shaft 54, is a gear 99 which meshes with a gear 100 loosely mounted upon the intermediate driving shaft 75. Feathered upon the shaft 54 adjacent to the gear 99 so as to be rotated therewith but slideable thereon is a gear 101 which is adapted to be moved into engagement with a gear 102 which is feathered upon the shaft 75 so as to be rotated therewith but slideable thereon. A gear 103 is feathered upon the press driving shaft 34 so as to be rotated therewith but so as to slide thereon, the said gear 103 being adapted to be moved into mesh with either the gear 100 or the gear 102. The hubs of the gears 100 and 102 are adapted to inter-engage whereby the gear 100 may be caused to rotate with the shaft 75. The sleeve 98 on the shaft 60, the shaft 78, the shaft 60, and the shaft 39 are provided with gears 104, 105, 106, 107, and 108, respectively, corresponding to the gears 99, 100, 101, 102 and 103, as above described, and mounted similarly thereto. The sleeve 98 mounted on the shaft 52, the shaft 74, the shaft 52, and the shaft 32, are provided with gears 109, 110, 111, 112, and 113, respectively, corresponding to the gears 99, 100, 101, 102 and 103, as above described, and mounted similarly thereto. The sleeve 98 mounted upon the shaft 59, the shaft 77, the shaft 59, and the shaft 37, are provided with gears 114, 115, 116, 117 and 118, respectively, corresponding to the gears 99, 100, 101, 102 and 103, as above described, and mounted similarly thereto. The sleeve 98 mounted upon the shaft 51, the shaft 73, the shaft 51, and the shaft 30, are provided with gears 119, 120, 121, 122, and 123, respectively, corresponding to the gears 99, 100, 101, 102 and 103, as above described, and mounted similarly thereto.

100, 101, 102, and 103, as above described, and mounted similarly thereto. The sleeve 98 mounted upon the shaft 57, the shaft 76, the shaft 57 and the shaft 35, are provided with gears 124, 125, 126, 127 and 128, respectively, corresponding to the gears 99, 100, 101, 102 and 103, as above described, and mounted similarly thereto.

We refer now to Fig. 9 for a partial explanation of the driving mechanism. If it is desired to drive the shaft 34 by means of the motor P through the variable speed mechanism W and to drive the shaft 39 from the motor R through the variable speed mechanism X, the gears 99, 100, 103 and 102 at one side of the machine would be secured in the positions shown in solid lines, while the gear 101 would be moved to the position shown in dotted lines. With the clutch 64 thrown into operation, the shaft 54 will be rotated and through the medium of the mechanism W the sleeve 98 will be rotated, rotating with it the gear 99 and through the medium of the gear 100 rotating the gear 103 and the shaft 34, the shaft 75 remaining idle. At the same time the gears 104, 103, 108 and 107 would be secured in the positions shown in solid lines, while the gear 106 would be moved to the position shown in dotted lines. Power is then transmitted from the motor R through the shaft 60, variable speed mechanism X, sleeve 98, and gears 104, 105 and 108 to the shaft 39, the shaft 78 remaining idle.

If it were desired to drive the shaft 34 through the variable speed mechanism W and to drive the shaft 39 through the variable speed mechanism X, both from the motor P, the clutch 64 would be thrown into operation and the driving chain 70 connecting the motor R with the shaft 60 would be thrown out of operation by being removed from the driving wheels 71-72, or in any other suitable manner as by the use of a clutch of any appropriate type. The gears would all be secured in the positions shown in solid lines. Power would then be applied from the motor P through the shaft 54, the variable speed mechanism W, the sleeve 98 and the gears 99, 100 and 103 to the shaft 34; at the same time power would be applied from the shaft 54 through the gears 101-102 to the shaft 75, through the chain 85, to the shaft 78, through the gears 107, 106 to the shaft 60, through the variable speed mechanism X, the sleeve 98, and the gears 104, 105 and 108 to the shaft 39. If it were desired to drive the shaft 39 through the variable speed mechanism X and to drive the shaft 34 through the variable speed mechanism W from the motor R instead of from the motor P, this would be accomplished by driving the shaft 60 from the motor R instead of driving the shaft 54 through the clutch 64 as just de-

scribed, the connections otherwise being precisely the same.

If it is desired to drive the shafts 34 and 39 from the motor P both through the variable speed mechanism W, the driving chain 70 from the motor R will be thrown out of operation and the clutch 64 thrown into engagement; the shaft 54 would thus be driven by the motor P, from which motion would be transmitted through the variable speed mechanism W to the sleeve 98, and through the gears 99, 100 and 103 to the shaft 34, said gears being secured in the position shown in solid lines. For transmission from the gear 100 to the shaft 39, the gears 102, 108 and 106 would be moved to the positions shown in dotted lines. The shaft 75 would then be rotated in unison with the gear 100, rotation being thus transmitted through the chain 85 to the shaft 78, and through the gears 107 and 108 to the shaft 39.

If it were desired to drive the shafts 34 and 39 from the motor R both through the variable speed mechanism X, it would be necessary to throw the clutch 64 out of operative engagement. The gears 104, 105 and 108 would be secured in the position shown in solid lines, while the gears 107, 103 and 101 would be secured in the positions shown in dotted lines. Power would then be transmitted from the motor R to the shaft 60, through the variable speed mechanism X to the sleeve 98, and through the gears 104, 105 and 108 to the shaft 39. At the same time the shaft 78 would be rotated by reason of the clutching engagement of the gears 105 and 107; transmitting motion through the chain 85 to the shaft 75, from which motion would be transmitted through the gears 102 and 103 to the shaft 34.

In Fig. 9, the motor Q which is shown in dotted lines in Fig. 6 is omitted, since it is sometimes desired to operate without this motor being provided. When the motor Q is provided and it is desired to operate without using it, its driving chain 70 is removed or otherwise thrown out of operation. If it were desired to use the motor Q in place of the motor P, the driving chain 70 of such motor Q would be placed in operation while the clutch 64 would be opened, the connections being otherwise as above described.

The motors M, N and O and the driving mechanism located between the motors M and O constitute the equivalent of the motors R, Q and P and the driving mechanism located between the motors R and P as above described. Inasmuch as the operation of the motors M, N and O and their connected parts is similar to that of the motors R, Q and P and their connected parts as above described, it is believed to be unnecessary to further describe such parts herein.

If the clutches 64 and 67 be thrown out of operation and the clutches 63 and 68 be thrown into operation, the motors O and P can be employed in connection with the driving elements located between said two motors, comprising the variable speed mechanisms U and V, respectively.

With the press equipped with six motors as shown, including the motors N and Q in dotted lines, it will be evident that the press sections A and C can be run by the motor M by the use of the variable speed mechanism S; the sections B and D by the motor N using the variable speed mechanism T; the sections E and G by the motor P, using the variable speed mechanism U; the sections F and H by the motor O using the variable speed mechanism V; the sections I and K by the motor Q using the variable speed mechanism W; and the sections J and L by the motor R using the variable speed mechanism X. If desired, the chain 79 may be used, the motors M and N then operating the sections A, B, C and D; the chain 82 can be used, the motors O and P then running the sections E, F, G and H; and the chain 85 can be used, the motors Q and R then running the sections I, J, K and L. In this proposed operation of the press, the webs from sections A and C would preferably be run over the former 21, the webs from the sections B and D over the former 22, the webs from the sections E and G over the former 23, the webs from the sections F and H over the former 24, the webs from the sections I and K over the former 25, and the webs from the sections J and L over the former 26, the press as a whole being thus operated as six quadruples producing six different sixteen page papers.

If it is desired to operate the press as a whole as four sextuples to produce four twenty-four page papers in lieu of six sixteen page papers, the press sections A, C and E may be run by the motor M by the use of the variable speed mechanism S using the former 21; press sections B, D and F may be run by the motor O using the variable speed mechanism T and the former 22; sections G, I and K may be run by the motor P using the variable speed mechanism W and the former 25; and press sections H, J and L may be run by the motor R using the variable speed mechanism X and the former 26. As an alternative connection and operation, press sections A, C and E may be run by the motor P using the variable speed mechanism U; sections B, D and F may be run by the motor N using the variable speed mechanism T; sections G, I and K may be run by the motor Q using the variable speed mechanism W; and the sections H, J and L may be run by the motor O using the variable speed mechanism V.

If it is desired to operate the press as a whole as three octuples to produce three thirty-two page papers, this may be accomplished by running press sections A, B, G and D either by the motor M using the variable speed mechanism S or by using the motor N and the variable speed mechanism T, the webs in either case being run over either the former 21 or the former 22; by running sections E, F, G and H either by the motor O using the variable speed mechanism V or the motor P using the variable speed mechanism U, the webs being run over either the former 23 or the former 24; by running the sections I, J, K and L by either the motor Q using the variable speed mechanism W or the motor R using the variable speed mechanism X, the webs being run over either the former 25 or the former 26.

It will be evident that other combinations for the production of either sixteen page papers, twenty-four page papers or thirty-two page papers may be readily worked out by the manipulation of the clutches and driving elements as above described in connection with Fig. 9. It will also be evident that various other-sized papers may be produced by a different distribution of the webs from the various press sections. For example, if it were desired, the motors N and O might readily be employed together in connection with the variable speed mechanism T for operating the press sections A, B, C, D, E and F, the webs from the various sections being distributed between the formers 21, 22, 23 and 24 as might be desired.

It is believed to be unnecessary to set forth in detail the manner of operating the press by means of the motors M, O, P and R when the motors N and Q are omitted, inasmuch as this will be readily understood. The press can then be driven by the motors M, O and R as above described for producing three thirty-two page papers; the press can then be operated as above described by the motors M, O, P and R for producing four twenty-four page papers. When it is desired to produce six sixteen-page papers, press sections A and C may be run through the medium of the variable speed mechanism S and sections B and D through the medium of variable speed mechanism T both from the motor M. The motor P can then be used with the variable speed mechanism U for running sections E and G and the motor O in connection with the variable speed mechanism V for running the sections F and H. The motor R can be used for driving the sections J and L through the variable speed mechanism X and for driving the sections I and K through the variable speed mechanism W.

What we claim as our invention and desire to secure by Letters Patent, is—

1. In a printing press, the combination of twelve press sections, driving means for said press sections, and means for connecting said driving means with said press sections for driving the press as six quadruples, as four sextuples, or as three octuples.
2. In a printing press, the combination of twelve press sections, six motors for driving said sections, six variable speed mechanisms independent of said motors, and means for connecting each of said motors with two of said sections through one of said variable-speed mechanisms for driving said sections independently as six quadruples or for connecting four of said motors with said twelve sections through four of said variable-speed mechanisms for driving said sections independently as four sextuples or for connecting three of said motors with said twelve sections through three of said variable-speed mechanisms for driving said sections independently as three octuples.
3. In a printing press, the combination of two press sections arranged in longitudinal alinement with each other, a third press section arranged in alinement therewith, a line of shafting extending longitudinally of said press sections, connections between said shafting and said press sections, means located between said first-named two sections and said third section for driving said shafting for operating said press sections, angle-bars over which the webs printed by said sections may be turned and associated to run longitudinally of said sections, and means located between said first-named two sections and said third section for giving the associated webs from said sections a longitudinal central fold.
4. In a printing press, the combination of two press sections arranged in longitudinal alinement with each other, a third press section arranged in alinement therewith, a line of shafting extending longitudinally of said press sections, connections between said shafting and said press sections, means located between said first-named two sections and said third section for driving said shafting for operating said press sections, angle-bars over which the webs printed by said sections may be turned and associated to run longitudinally of said sections, means located between said first-named two sections and said third section for giving a central longitudinal fold to the webs, and other alternative means located at the end of said third section for giving a central longitudinal fold to said webs.
5. In a printing press, the combination of two press sections arranged in longitudinal alinement with each other, a third press section arranged in alinement therewith, two other press sections arranged in longitudinal alinement with each other alongside of said first-named two sections, a sixth press section arranged in longitudinal alinement with said second-named two alined sections alongside of said third section, angle-bars over which the webs printed by said sections may be turned and associated as desired to run together longitudinally of said sections at either side of the press, a line of shafting extending longitudinally of the said press sections at each side of the press, connections between said lines of shafting and said sections respectively, means for driving said shafting for operating said press sections, and means located between said third and sixth press sections and the remaining press sections for giving the associated webs from said press sections a longitudinal central fold.
6. In a printing press, the combination of two press sections arranged in longitudinal alinement with each other, a third press section arranged in alinement therewith, two other press sections arranged in longitudinal alinement with each other alongside of said first-named two sections, a sixth press section arranged in longitudinal alinement with said second-named two alined sections alongside of said third section, angle-bars over which the webs printed by said sections may be turned and associated as desired to run together longitudinally of said sections at either side of the press, a line of shafting extending longitudinally of the said press sections at each side of the press, connections between said lines of shafting and said sections respectively, means for driving said shafting for operating said press sections, means located at the ends of said third and sixth press sections respectively for giving the associated webs from said press sections a longitudinal central fold, and other means located between said third and sixth press sections and the remaining press sections adapted alternatively for giving the associated webs from said press sections a longitudinal central fold.
7. In a printing press, the combination of two alined press sections, angle-bars over which the webs printed by said sections may be turned and associated to run longitudinally of said sections, means located between said press sections for giving the associated webs a central longitudinal fold, two variable-speed mechanisms, and means for driving said press sections either separately through said two variable-speed mechanisms or in unison through one of said variable-speed mechanisms.
8. In a printing press, the combination of two alined press sections, angle-bars over

- which the webs printed by said sections may be turned and associated to run longitudinally of said sections, means located between said press sections for giving the associated webs a central longitudinal fold, and means located between said two press sections for driving said press sections in unison.
9. In a printing press, the combination of two alined press sections, two other alined press sections located alongside of said first-named two sections, angle-bars over which the webs printed by said sections may be turned and associated to run longitudinally of said sections, means located between the alined press sections at each side of the press for giving the associated webs a central longitudinal fold, four variable-speed mechanisms, and means for driving said press sections either separately through said four variable-speed mechanisms or in unison through one of said variable-speed mechanisms.
10. In a printing press, the combination of two alined press sections, two other alined press sections located alongside of said first-named two sections, angle-bars over which the webs printed by said sections may be turned and associated to run longitudinally of said sections, means located between the alined press sections at each side of the press for giving the associated webs a central longitudinal fold, alined driving shafts extending longitudinally of the press sections at each side of the press, an intermediate driving shaft between the said alined shafts at each side of the press, means for connecting each of said intermediate shafts with either or both of the alined shafts at that side of the press, and means for driving said intermediate shafts.
11. In a printing press, the combination of two alined press sections, angle-bars over which the webs printed by said sections may be turned and associated to run longitudinally of said sections, means located between said press sections for giving the associated webs a central longitudinal fold, means located between said two press sections for driving either or both of said sections, and means located at one end of said alined sections for alternatively driving either or both of said sections.
12. In a printing press, the combination of twelve press sections, six motors for driving said sections, and means for connecting each of said motors with two of said sections for driving them independently as six quadruples or for connecting four of said motors with said twelve sections for driving them independently as four sextuples or for connecting three of said motors with said twelve sections for driving them independently as three octuples, said connections comprising six variable speed mechanisms adapted to be manipulated whereby each combination of press sections working in coördination may be driven independently of the remaining sections.
13. In a printing press, the combination of twelve press sections, four motors for driving said sections, and means for connecting two of said motors with four press sections each and the other two motors with two press sections each for driving said twelve press sections as six quadruples, said connections comprising six variable speed mechanisms adapted to be manipulated whereby each of said six quadruples may be driven independently of the remaining sections.
14. In a printing press, the combination of two alined press sections, angle-bars over which the webs printed by said sections may be turned and associated, means located between said two press sections for driving either or both of said press sections, and means located at one end of said alined sections for alternatively driving either or both of said sections.
15. In a printing press, the combination of two alined press sections, angle-bars over which the webs printed by said sections may be turned and associated, means located at one end of said alined press sections for driving either or both of said sections, and other means located at the opposite end of said alined press sections for alternatively driving either or both of said sections.
16. In a printing press, the combination of two alined press sections, angle-bars over which the webs printed by said sections may be turned and associated, means located between said two press sections for driving either or both of said sections, means located at one end of said alined sections for alternatively driving either or both of said sections, and other means located at the opposite end of said alined sections for alternatively driving either or both of said sections.
17. In a printing press, the combination of two press sections, alined driving shafts extending adjacent to said press sections, connections between said shafts and said press sections respectively for driving said press sections, an intermediate shaft in alignment with said two shafts, a fourth shaft in alignment with said three shafts at one end, a fifth shaft in alignment with said four shafts at the opposite end, means for driving said intermediate shaft, other means for driving said fourth shaft, other means for driving said fifth shaft, and means for connecting each two adjacent shafts as desired.
18. In a printing press, the combination of two press sections, alined driving shafts extending adjacent to said press sections, connections between said shafts and said press sections respectively for driving said

- press sections, a third shaft in alinement with said two shafts at one end, a fourth shaft in alinement with said three shafts at the opposite end, means for driving said third shaft, means for driving said fourth shaft, and means for connecting said shafts in series as desired.
19. In a printing press, the combination of two press sections arranged in alinement with each other, a third press section arranged in alinement therewith, two other press sections arranged in alinement with each other alongside of said first-named two sections, a sixth press section arranged in alinement with said second-named two alined sections alongside of said third section, a line of shafting extending adjacent to the said three press sections at each side of the press, connections between said lines of shafting and said sections respectively, and means connected with said lines of shafting between the third and sixth press sections and the remaining press sections for driving said lines of shafting either separately or in unison for operating said press sections.
20. In a printing press, the combination of two press sections arranged in alinement with each other, a third press section arranged in alinement therewith, two other press sections arranged in alinement with each other alongside of said first-named two sections, a sixth press section arranged in alinement with said second-named two alined sections alongside of said third section, a line of shafting extending longitudinally of the press at each side adjacent to the three sections at that side, connections between said lines of shafting and said sections respectively, and means located at the ends of said third and sixth press sections for driving said lines of shafting either separately or in unison for operating said press sections.
21. In a printing press, the combination of two press sections arranged in alinement with each other, a third press section arranged in alinement therewith, two other press sections arranged in alinement with each other alongside of said first-named two sections, a sixth press section arranged in alinement with said second-named two alined sections alongside of said third section, a line of shafting extending longitudinally of the said press sections at each side of the press, connections between said lines of shafting and said sections respectively, means located at the ends of said third and sixth press sections for driving said shafting for operating said press sections, and other means located between the third and sixth press sections and the remaining press sections adapted alternatively for driving said shafting for operating said press sections.
22. In a printing press, the combination of two press sections, two oppositely-disposed driving shafts, means for connecting said shafts with said press sections respectively for operating the same, two variable speed mechanisms, means for driving said two variable speed mechanisms in unison, and means connecting said shafts with said variable speed mechanisms respectively.
23. In a printing press, the combination of two press sections, two oppositely-disposed driving shafts, means for connecting said shafts with said press sections respectively for operating the same, two variable speed mechanisms, and means for driving said shafts either through the medium of said two variable speed mechanisms respectively or through the medium of one only of said two variable speed mechanisms.
24. In a printing press, the combination of two press sections, two oppositely-disposed driving shafts, means for connecting said shafts with said press sections respectively for operating the same, two variable speed mechanisms, two main driving shafts, means for driving said last-named shafts independently of each other, means for driving said first-named two shafts from said main driving shaft through the medium of said two variable speed mechanisms respectively, and means for alternatively connecting said two main driving shafts together for operation in unison.
25. In a printing press, the combination of two press sections, two oppositely-disposed driving shafts, means for connecting said shafts with said press sections respectively for operating the same, a variable speed mechanism, a main driving shaft, means for driving said main driving shaft, and means for driving said first-named two shafts from said main driving shaft through the medium of said variable speed mechanism.
26. In a printing press, the combination of two press sections, two oppositely-disposed driving shafts, means for connecting said shafts with said press sections respectively for operating the same, two variable speed mechanisms, and means for driving said shafts through the medium of said two variable speed mechanisms respectively either in unison or independently of each other.
27. In a printing press, the combination of two press sections, two oppositely-disposed driving shafts, means for connecting said shafts with said press sections respectively for operating the same, two variable speed mechanisms, two main driving shafts, means for driving said last-named two shafts either independently of each other or in unison, and means for driving said first-named two shafts either from both of said main driving shafts through the medium of

said two variable speed mechanisms respectively or from one of said main driving shafts through the medium of one of said variable speed mechanisms.

28. In a printing press, the combination of a press section, a shaft for operating said press section, a main driving shaft parallel with said first-named shaft, an intermediate shaft, means for driving said main driving shaft, a gear rotatable with said main driving shaft, a second gear loosely mounted on said intermediate shaft meshing with said first-named gear, and a third gear feathered on said first-named shaft adapted to be thrown into operative engagement with said second gear for driving said first-named shaft.

29. In a printing press, the combination of a press section, a shaft for operating said press section, a main driving shaft parallel with said first-named shaft, an intermediate shaft, means for driving said main driving shaft, a gear rotatable with said main driving shaft, a second gear loosely mounted on said intermediate shaft meshing with said first-named gear, a third gear meshing with said second gear and adapted to drive said first-named shaft, and clutching means adapted alternatively to be thrown into operation for causing said intermediate shaft to rotate with said second gear.

30. In a printing press, the combination of a press section, a shaft for operating said press section, a main driving shaft parallel with said first-named shaft, an intermediate shaft, means for driving said main driving shaft, a gear rotatable with said main driving shaft, a second gear loosely mounted on said intermediate shaft meshing with said first-named gear, a third gear adapted to rotate with said intermediate shaft, clutching mechanism for connecting said second gear with said third gear, and a fourth gear feathered upon said first-named shaft adapted to mesh either with said second gear or with said third gear.

31. In a printing press, the combination of a press section, a shaft for operating said press section, a main driving shaft parallel with said first-named shaft, an intermediate shaft, means for driving said main driving shaft, a gear rotatable with said main driving shaft, a second gear loosely mounted on said intermediate shaft meshing with said first-named gear, a third gear feathered upon said intermediate shaft and adapted to be moved longitudinally of said intermediate shaft into engagement with said second gear for causing the intermediate shaft to rotate with said second gear, and a fourth gear feathered upon said first-named shaft adapted to mesh with said second gear or with said third gear.

32. In a printing press, the combination of a press section, a shaft for operating said

press section, a main driving shaft parallel with said first-named shaft, an intermediate shaft, means for driving said main driving shaft, a gear rotatable with said main driving shaft, a second gear loosely mounted on said intermediate shaft meshing with said first-named gear, a third gear adapted to rotate with said intermediate shaft, a fourth gear feathered upon said first-named shaft adapted to mesh either with said second gear or with said third gear, and a fifth gear feathered upon said main driving shaft adapted to be moved either into or out of mesh with said third gear.

33. In a printing press, the combination of a press section, a shaft for operating said press section, a main driving shaft parallel with said first-named shaft, an intermediate shaft, means for driving said main driving shaft, a gear mounted on said main driving shaft, variable speed mechanisms serving to connect said gear with said main driving shaft, a second gear loosely mounted on said intermediate shaft meshing with said first-named gear, and a third gear meshing with said second gear adapted to drive said first-named shaft.

34. In a printing press, the combination of a press section, a shaft for operating said press section, a main driving shaft parallel with said first-named shaft, an intermediate shaft, means for driving said main driving shaft, a gear rotatable with said main driving shaft, a second gear loosely mounted on said intermediate shaft meshing with said first-named gear, a third gear meshing with said second gear, and adapted to drive said first-named shaft, means for causing said intermediate shaft to rotate with said second gear, a second press section, and means for driving said second press section from said intermediate shaft.

35. In a printing press, the combination of a press section, a shaft for operating said press section, a main driving shaft parallel with said first-named shaft, an intermediate shaft, means for driving said main driving shaft, a gear rotatable with said main driving shaft, a second gear loosely mounted on said intermediate shaft meshing with said first-named gear, a third gear meshing with said second gear and adapted to drive said first-named shaft, means for causing said intermediate shaft to rotate with said second gear, a second press section, a shaft for operating said second press section, a variable speed mechanism, and means for driving said last-named shaft either directly from said intermediate shaft or through the medium of said variable speed mechanism.

36. In a printing press, the combination of a press section, a shaft for operating said press section, a main driving shaft parallel with said first-named shaft, an intermediate shaft, means for driving said main driving

shaft, a gear mounted on said main driving shaft, a variable speed mechanism serving to connect said gear with said main driving shaft, a second gear loosely mounted on said 5 intermediate shaft meshing with said first-named gear, a third gear meshing with said second gear and adapted to drive said first-named shaft, means for causing said intermediate shaft to rotate with said second 10 gear, a second press section, a shaft for operating said second press section, a second variable speed mechanism, and means for driving said last-named shaft either directly from said intermediate shaft or through the 15 medium of said second variable speed mechanism.

37. In a printing press, the combination of two press sections, two oppositely-disposed shafts for driving said press sections 20 respectively, two main driving shafts, two intermediate shafts interposed between the first-named shafts and the main driving shafts, means for causing said intermediate shafts to rotate together, means for driving 25 one of said main driving shafts, means for driving one of said first-named shafts and the corresponding intermediate shaft from said main driving shaft, and means for driving the other one of said first-named shafts 30 from the other one of said intermediate shafts.

38. In a printing press, the combination of two press sections, two oppositely-disposed shafts for driving said press sections respectively, two main driving shafts, two intermediate shafts interposed between the first-named shafts and the main driving shafts, means for causing said intermediate shafts to rotate together, means for driving 40 one of said main driving shafts, means for driving one of said first-named shafts and the corresponding intermediate shaft from said main driving shaft, means for driving the other main driving shaft from the other 45

one of said two intermediate shafts, and 45 means for driving the other one of said first-named two shafts from said last-mentioned main driving shaft.

39. In a printing press, the combination of two press sections, two oppositely-disposed 50 shafts for driving said press sections respectively, two main driving shafts, two intermediate shafts interposed between the first-named shafts and the main driving shafts, means for causing said intermediate 55 shafts to rotate together, means for driving one of said main driving shafts, means for driving one of said first-named shafts and the corresponding intermediate shaft from said main driving shaft, means for driving 60 the other main driving shaft from the other one of said two intermediate shafts, and means for driving the other one of said first-named two shafts either from the last-named intermediate shaft or from the last-mentioned main driving shaft. 65

40. In a printing press, the combination of two press sections, two oppositely-disposed shafts for driving said press sections respectively, two main driving shafts, two intermediate shafts interposed between the first-named shafts and the main driving shafts, means for causing said intermediate shafts to rotate together, means for driving 70 one of said main driving shafts, means for driving one of said first-named shafts and the corresponding intermediate shaft from said main driving shaft, means for driving the other main driving shaft from the other one of said two intermediate shafts, variable 80 speed mechanism, and means for driving the other one of said first-named two shafts either directly from the last-mentioned intermediate shaft or through the medium of said variable speed mechanism from the last- 85 mentioned main driving shaft.
